HENRY MILLER.

INVENTOR

BY *Victor J. Evans*

ATTORNEY

WITNESS:

G. J. Dannel

UNITED STATES PATENT OFFICE

HENRY MILLER, OF LINCOLN, NEBRASKA

SHIRT

Application filed August 23, 1929. Serial No. 387,977.

This invention relates to shirts and is herein illustrated as embodied in a man's shirt.

One of the objects of the invention is to provide an under garment which, while allowing of free bodily movement of a wearer, affords an additional protective covering for parts of the body which are susceptible to cold.

10 Articles of apparel worn by men or boys generally include a shirt and a pair of trousers, the top of the latter always ending about the waist line, while the lower part or skirt invariably reaches below and inside 15 of the top of the trousers, thereby providing a double covering for the buttocks and abdomen, the thorax, which is more susceptible to cold than adjacent parts, being thus provided with less covering than the pelvic region. Vests or waistcoats are worn, of course, but while these garments reach over the top of the trousers and therefore furnish three plies of material, the chest and shoulders are still provided with less covering.

25 The primary object of the invention is therefore to provide a shirt the upper front and back portions of which, above the garments worn on the lower limbs and reaching to the waist, are so constructed as to protect 30 the chest and shoulders of a wearer, particularly when it becomes necessary to remove part of the upper outer coverings, such as a coat or vest.

Another object of the invention is the provision of a shirt in which, without the addition of a separate strip for reinforcing the shirt at points where fastening elements, such as buttons, are attached, a pair of plies are provided on which to mount the buttons 40 and to insert the buttonholes therefor.

Similarly, pockets are provided in my improved shirt, by simply slitting the outer or superposed ply and then suitably stitching both plies to connect with the opposite ends 45 of the slits and form the outer boundaries of the pockets, to attain a further object of the invention.

The general lines of construction of the shirt may be in accordance with standard 50 cutting and sewing practice and any style

effect desired may be worked into the body of the shirt without sacrificing the practical advantages which my invention provides.

For example, the shirt may be made with 55 short or long sleeves, with an open collar neck, or a closed collar effect may be incorporated.

Other objects and advantages of the invention will be hereinafter specifically 60 pointed out, or will become apparent, as the specification proceeds.

With the above indicated objects in view, the invention resides in certain novel constructions and combinations and arrangement of parts, clearly described in the following specification and fully illustrated in the accompanying drawings, which latter show an embodiment of the invention as at 70 present preferred.

Figure 1 is a front elevational view of a shirt, partly broken away.

Figure 2 is a fragmentary rear elevational view of the same.

Figure 3 is an enlarged vertical sectional 75 view on the line 3—3 of Figure 1.

Figure 4 is a plan view of a front protective section.

Figure 5 is a plan view of back protective section.

Figure 6 is a fragmentary sectional view 80 similar to part of Figure 3, but showing a slightly modified form of construction.

In the embodiment of the invention selected for illustration in the drawings, the 85 shirt includes a front 10, which is openable on the longitudinal central line, there being a row of buttons 11 and mating buttonholes 12, while a rolled or double collar is attached around the neck opening of the shirt. 90

The skirt or lower part of the front 10 is formed with a pair of like portions 14 and 15 to the tops of which are stitched at seams 16 the outer front sections or plies 17 and 18, as well as inner protective sections 19 and 20, the respective sections having converging lower edges and being preferably provided adjacent their outer edges, below the sleeves 21, with apertures 22 for ventilating purposes, the upper edges of the por- 100

tions 14 and 15 follow the shape of the lower edges of the plies 17, 18, 19 and 20.

Stitched at its lower edge 23 to the rear lower body portion 24 of the back 25 of the shirt is an outer section or ply 26 having a shoulder extension, and to the edge 27 of which are stitched in seams 28 the top edges 29 of the respective front sections 17 and 18, the seams being formed by rounding the edge of the extension upwardly, and rounding the upper edge of one of the inner front plies downwardly as shown in Figure 3, while the outer edges, as at 30, of said sections 17 and 18 are stitched in lateral seams 31 to the outer edge 32 of the back section 26, together with the outer edges of the inner back ply 33, which latter is a continuation of the lower back portion 24. The outer edges of the inner sections 19 and 20, which are like those shown at 30, are also stitched in the seams 31, while the top edges of said inner sections are also stitched in the seams 28, with the edges of the sections 17 and 18, as clearly shown.

The outer edges of the respective lower portions 14, 15 and 24 are stitched in lateral seams 34 which are a continuation of the seams 31. The sections 17, 18, 19, 20, 26 and 33 are suitably cut at their top central portions to receive the collar 13.

Stitched also in the seams 28, as well as to the top of the back inner section 33 is a strip of lining 35, the latter being also stitched to the base of the collar 13, while the opposite terminals of said strip, together with part of the outer edges of the double plies 17—20, 26 and 33, are stitched in seams 36 to the sleeves 21.

The plies 17 and 18 are slit at 37 and are provided with substantially triangle shaped reinforcing tabs 38 at the opposite ends of the slits, while rectangularly disposed lines of stitches 39 attach the said plies to the inner plies 19 and 20 thereby forming pockets 40, a strip 41 being preferably attached at the slit 37 to the material forming the pocket. These pockets may also have flaps 42 provided with linings as shown in Figure 3.

As lines of stitches 43 and 44 also attach the inner edges of the double front plies, one of which edges is shown at 45, the necessity of using reinforcing strips or separate facings, on which to mount the buttons 11 or install the buttonholes 12, is dispensed with.

While the shirt may be manufactured from any suitable material I find it an advantage to use material in the inner protective plies 19 and 20 differing from the material of the outer plies; and as both inner and outer plies are stitched to the bottom portions 14 or 15 I also find that material which could not otherwise be easily used may be utilized for these bottom por-

tions, thereby effecting economy of material.

As, however, the lower bottom portions and inner top plies may be continuous, Figure 6 illustrates such a construction, the bottom 15' and inner ply 20' being formed in one piece, while an outer ply 18' is attached thereto.

The hereinbefore described construction admits of considerable modification without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

What is claimed as new is:

A shirt comprising a back body portion, a pair of co-acting single lower front portions having their lateral edges secured to the lateral edges of the back body portion, an outer back ply having its lower edge secured to the back body portion and extending above the upper edge thereof to provide a shoulder extension, a pair of double top front plies having their upper edges secured to the shoulder extension, seams formed with the extension by rounding the edge thereof upwardly and formed with the inner front plies by rounding the upper edges thereof downwardly, said seams arranged at the point of connection of the extension with the double top front plies and having their rounded portions arranged in hooked formation with each other, the lateral edges of the double top front plies being secured to the back body and outer back ply, a collar secured to the extension and double top front plies, sleeves secured to the extension, double top front plies and back body portion respectively, said pair of co-acting single lower front portions having their upper edges secured to the double top front plies and said double top front plies having button and buttonholes along overlapping edges thereof.

In testimony whereof I hereby affix my signature.

HENRY MILLER.
